ARCH FILING DEVICE

Maurice A. Lambrix, Cleveland, Ohio, assignor to All-Matic Corporation, Hudson, Ohio, a corporation of Ohio

Filed Sept. 1, 1960, Ser. No. 53,519
2 Claims. (Cl. 129—10)

This invention relates to improvements in paper filing devices of the type commonly referred to as the swung out arch type, constituting a mounting adapted to be affixed to a suitable board or other carrier, and having a pair of separated impaling pins adapted to pass through perforations in papers for convenient temporary binding or storage, and whereby such papers or documents may be held in order while being readily raised and slid upwardly and around the transfer arch portions for convenient access to papers beneath.

In filing devices of this character, it is desirable that the arch elements are adapted to revolve about vertical axes and have their forward downwardly pointed ends coacting with the upper ends of the impaling pins, while being enabled to be swung simultaneously outwardly from the impaling pins, and to be similarly returned to securing position engaging the pins.

The general object of the present invention is to so construct such a device that it may be cheaply manufactured, durable in use, and convenient to operate.

A more specific object of the invention is to provide in such a filing device a novel form of connecting and actuating mechanism for effecting simultaneous swinging or partial rotation of the arch members, and which likewise shall be simple, effective, and be capable of being cheaply manufactured and not likely to get out of order.

A further specific object is to so construct an interconnecting operating element engaging gear-like teeth rigid with each arch member and which shall constitute a single flat strip easily mounted in position, and so interconnected with elements at the lower stationary axis ends of the arches as to be self-guiding, and be provided with means for limiting the outward swinging movement of the arch members.

A still further object is to provide the yielding means so coacting with said interconnecting elements for operating the arches that the arches may be firmly but yieldingly held in normal securing position, and likewise be held in the spread or open position by the same means, and particularly it is desired that such means shall be extremely simple and effective in operation and may be readily assembled with the coacting parts.

A still further specific object is to so design the base or carrier portion of the filing device that it may be economically manufactured of sheet-like pressed metal or be cast of suitable light weight and easily die cast material.

Advantageous details of my improved filing device will become apparent in the following description which relates to the drawings, in which:

FIG. 1 is a plan view of a filing device constructed in accordance with the present invention;

FIG. 2 is a front or edge elevation of the same;

FIG. 3 is a sectional view through the base portion taken on a plane indicated by the line 3—3 of FIG. 1, and showing an impaling pin and transfer arch in elevation;

FIG. 4 is an enlarged detail of the connection between the arch and the swinging mechanism, and showing one of the spring means for holding the transfer arches in open or closed position;

FIG. 5 is an enlarged perspective view of the gear teeth and guiding surface member at the lower end of a transfer wire, and

FIG. 6 is a detail perspective view of the coacting

2

teeth and guide slot at one end of the interconnecting slide.

Describing the present illustrative embodiment by the use of reference numerals, the base portion as shown 5 comprises a substantially flat plate 1 having its perimeter shaped to conform to a cover, as appears in FIG. 1, and having an ear 2 with a supporting opening or eye 3. Above this plate 1 is the top plate 5 having separated raised boss portions 6 and 7 formed to receive the lower 10 ends of the rigidly supporting impaling pins 10 and 11. These pins may be made of hollow tubing with an enlarged bead for engaging the top of the boss and a cylindrical portion. The lower end of each pin tube is fitted tightly into an inturned socket 12, below which 15 the tube is spread, as indicated in FIG. 3, for firmly securing these impaling pins.

The upper and lower plates may be secured together by any suitable means, such as rivets 15, and likewise may be affixed by screws or the like to the carrier board. 20 Holes for this purpose are indicated at 16.

The shape of both the plates of the base is elongated, and the upper or rear portion of each is offset upwardly, and the rear portion of the top plate is offset upwardly to form a housing for the operating parts and mounting 25 25 of the transfer arches. The lower plate 1 is offset slightly at 17 for a portion conforming to the area of the offset 18 forming said housing part of the upper plate.

The transfer arch elements 20 and 21 have straight vertical portions, the lower ends of which are fitted into 30 bearings 22 and 23 in the housing 18, and pass through the bearings and are fitted with the toothed partial gears and guiding elements within the housing between the portions 17 and 18, as will presently be described.

The arch members are curved forwardly from the 35 vertical portions and then downwardly where reduced end portions, as at 25, fit into the cutaway upper ends of the tubular impaling pins. Here, it will be seen that approximately one-half of the tubular portion is cut downwardly a short distance from the end, as at 26, to form a 40 stop and receptacle for the forward swingable ends of the transfer arches.

The means for swinging the arches simultaneously from the storing portions, shown in FIGS. 1, 2, and 3, to the open or filing position, each being swung outwardly away from its companion, is indicated in the detail of 45 FIG. 4, and the means for retaining the arches in the closed and open position, respectively, will now be described.

A segmental gear and guide element, shown as having two full teeth and a side of a third, is formed rigid with 50 the lower end of each transfer arch member. Referring to FIGS. 5 and 6, the parts shown correspond to the left end of FIG. 1. On the segmental gear and guide element of the arch 20, such teeth are shown at 30, and the cylindrical portion is indicated at 31.

55 The teeth 30 fit and coact with two or more teeth 34 formed on the end of an interconnecting flat bar 35. It will be noted that there are two arms extending from the body of the bar, as indicated at 36, on which the teeth 34 are formed, and at 37 spaced therefrom and parallel 60 to the sides, and hence to the longitudinal movement of the bar. The space between these two arms leaves a flat surface 38 which normally remains in contact with the cylindrical surface 31 as the attached arch makes its partial turn from closed to open position and back again.

65 This forms a guide for the bar, maintaining the teeth 30 and 34 in proper engaging position. This characteristic simplifies the construction and avoids the difficulty of attempting to closely fit and guide a reciprocating interconnecting rack bar by guides formed on housing parts to 70 attain the proper meshing of the actuating gear teeth. As indicated at the left in FIG. 1, the rack teeth 34

engage the gear teeth 30 at the side of the gear and guide elements toward the arch and pin 10, while at the other end of the bar 35 the teeth are at the side of the element away from the arch 21 and pin 11.

The inner end of the space between the two arms 36 and 37, indicated at 39, forms a stop limiting the longitudinal movement of the bar and correspondingly limiting the opening movement of the arches.

The interconnecting operating mechanism described lends itself to a simple effective resilient means for holding the arches in the closed or open position. Spring members formed of flat spring metal, each having an intermediate loop 40, and outwardly extending end portions 41 and 42, may engage notches formed in the ends of the housing portions and fit loosely between the portions 17 and 18 forming the housing, while the outer end engages a notch, as at 44, in the vertical flange at the end portion of the housing, and the other end of the spring engages a notch, such as at 45, adjacent to the teeth 30. In fact, as shown, the end 41 is engaging the side of one of the teeth 30, while the adjacent portion provides a clearance permitting the parts to assume the position shown in FIG. 4.

The pivoting notch 44 is in longitudinal alignment with the movement of the interconnecting rack bar 35 and 25 actually on a line passing through the axes of both of the gear and guide members and vertical parts of the arches. Thus, when the parts are in the closed positions, the spring end 41 is below the center or axis of the arch members, and the gears, and is tending to swing the forward extensions of the arches and hold them into tight engagement with their receiving notches at the upper ends of the impaling posts 10 and 11. When the arches are swung to open position, as indicated in solid lines in FIG. 4, the portion 41 of the spring is at the other side of the line passing through both the arch axes and gears, and thus exerts a pressure holding the arches outwardly.

It will be noted by comparing FIG. 1 and FIG. 4 that the interconnecting rack bar 35, when the arches are closed, is in a position at the right of that indicated in FIG. 4. When the arches are swung open, it will be seen that the gear teeth 34, having swung the arch 20 to the left aided by the springs, will have brought the surface 39 of the bar 35 into contact with the cylindrical portion 31 of the gear and guide element at the lower end of the member 20. When the arches are swung to closed position, engaging the posts 10 and 11, a stop is not needed, but it would be apparent that the shoulder 39a may then contact the cylindrical part 31a (FIG. 4), as appears in broken lines at the right in FIG. 1.

As previously indicated, the inner surface 38 of the arm 37 and the corresponding surface 38a at the right of FIG. 4 may each slide along the cylindrical surface of the partial gear member, assuring the proper tight engagement of the gear teeth at each end of the bar.

It will be apparent that the base and housing portions may be designed for artistic effect as well as strength by being appropriately ribbed, and it will also be seen that the raised portion 18 of the top plate 5 and the corresponding area of the bottom plate may form a housing closely fitting the simple flat rack bar 35, as well as confining the springs. This arrangement lends itself to most convenient construction and assemblage of the parts in the course of manufacture, as well as assuring retaining the parts in operative position, thus held against displacement throughout all sorts of motions to which the device may be subjected in use, shipping, etc.

It will also be seen that the mounting for the rigid impaling or paper-holding pins, as well as the bearing for the arches, may be formed with a minimum of expense, while suitable ribbing at the top portion, indicated at R, may add to the attractive appearance, and support the impaled ends of the papers.

It is to be understood that modifications of details may

be employed without departing from the spirit and scope of the invention as defined in the appended claims.

Having thus described my invention, what I claim is:

1. A filing device of the character described, including rigid impaling pins and cooperatively arranged transfer arches adapted to be simultaneously swung into and out of registering engagement with said pins, each of the arches having a vertical rotatable portion and each provided with a rigidly attached element having gear teeth and a cylindrical surface in the same circumference, a reciprocating flat rack bar extending between said elements and having separated arms embracing said elements, one of which arms carries rack teeth coacting with said gear teeth, and the other of which slidably engages the cylindrical surface for a guide holding said teeth in operative engagement, said rack teeth and gear teeth being on opposite sides of a line through the axes of the elements and vertical portions of the arches, resilient means for holding the arches in the open or closed positions, the reciprocating flat rack bar being guided by said elements and gear teeth and said resilient means engaging said elements, a housing having upper and lower parallel walls embracing said gear and guiding elements and said reciprocating rack, said resilient means comprising springs of flat metal positioned between said walls, and each shaped to form a U-shaped loop having outwardly oppositely extending end portions, one end of each of which is pivoted to the housing and the other end of which engages said gear elements and normally exerts pressure at one side or the other of a line through the axis of rotation of each of said gear elements, the pivots at the housing being positioned on said line through the axes whereby said springs act to hold the arch members either in open filing position or in closed position engaging the impaling pins

2. In a filing device of the character described, a combination with a base member adapted to be secured to a support, and a top member rigid therewith and having a raised transversely elongated housing portion provided with bearings, arch members having rotatable portions in said bearing members and extending over the housing, retaining impaling pins rigidly carried by the housing each adapted to be engaged by an arch member, means for swinging both arches comprising gear and guide elements rigid with said rotatable portions of the arch within the housing, each of said elements having gear teeth for a portion only of its circumference and having a circular portion in the same circumference, a reciprocating bar having separated arms at each end, one arm of which carries rack teeth engaging the gear teeth of said elements at the opposite side from the other with relation to its direction of reciprocating movement, and the other arm having a smooth bearing surface slidably engaging said cylindrical surface to accurately position the rack teeth in operative engagement with said gear teeth of the embraced element, and spring means within the housing for holding the swingable arches in closed or open position, said spring means comprising two members of flat spring metal strip each formed into a loop with its ends extending outwardly from the loop, one end of each spring member being pivotally seated in an end wall of the housing and positioned in a plane passing through the centers of said gear and guide members, and the other end engaging the gear element and acting to exert pressure at one side or the other of said plane.
